UNITED STATES PATENT OFFICE.

ANDREW H. WEIR, OF LOS ANGELES, CALIFORNIA.

DRAW-BAR FOR CARS.

SPECIFICATION forming part of Letters Patent No. 237,934, dated February 15, 1881.

Application filed May 11, 1880. (Model.)

To all whom it may concern:

Be it known that I, ANDREW H. WEIR, of the city and county of Los Angeles, and State of California, have invented an Improved Coupler and Draw-Head for Railroad-Cars; and I hereby declare the following to be a full, clear, and exact description thereof.

My invention relates to certain improvements in railroad-car draw-heads and couplers; and it consists in a novel construction of the fastenings whereby the draw-head is secured to the car.

Figures 1 and 2 are longitudinal vertical sections of my invention. Figs. 3 and 4 illustrate the manner of attaching the draw-heads to the car.

Let A represent the draw-head, and A' its shank or stem, said stem being provided with a wrought-iron washer, a, which comes behind the usual cast-iron follower and between it and the keys a'.

To fasten my draw-head to the cars the stem A' is provided with the key a' on each side, beveled so that a wrought-iron clasp, a², driven over them, will hold the two keys tight to the stem, and a small bolt, a³, runs transversely through the stem and keeps the band in place. The pull comes sidewise on these two keys, so that it will be impossible to break them or the other key or bolt, and it will be impossible to pull the draw-head out of the car. Usually the transverse key a⁴, against which the washer strikes, is driven through the stem, and the

stem is sometimes split when a heavy strain is given. In this the strain comes on the longitudinal keys, which are held by the clasp, and there is no danger of splitting the stem.

To show the manner of attaching the draw-heads to the cars, let S⁴ S⁴ represent the car-timbers. Fastened to them are the four cast-iron projecting blocks, W⁴ W⁴. Between these blocks, and abutting thereon, are the wrought-iron pieces or plates X⁴ X⁴, sliding in the grooves or guides M M, and provided with the spring q⁴, whereby the jerks of the car are broken. The draw-head A has a shank or stem, A', which passes through the plates X⁴ X⁴ and the spring q⁴, and is fastened by means of the head, as before shown.

Having thus described my invention, what I claim as new, and desire to secure by Letters Patent, is—

In combination with the draw-head A, with its shank or stem A', and washer a, the beveled keys a', band or clasp a², and securing-bolt a³, whereby the draw-head is secured to the cars firmly, and danger of splitting the stem avoided, substantially as and for the purpose herein described.

In witness whereof I have hereunto set my hand.

ANDREW H. WEIR.
